UNITED STATES PATENT OFFICE

2,528,930

STRAW PACKAGING MACHINE

John B. West, Baltimore, Md., assignor to Maryland Paper Products Company, Inc., Baltimore, Md., a corporation of Maryland

Application June 14, 1946, Serial No. 676,759

4 Claims. (Cl. 93—3)

1

The present invention relates to machines for forming wrappers, placing one or more straws therein and sealing the ends of the wrappers.

More particularly the invention relates to certain new and useful improvements made to the Toolan Straw Packaging Machine of Letters Patent #2,146,490 issued February 7, 1939.

The present invention seeks to provide an improved means for cutting the continuous wrapper into sections of predetermined lengths and pushing them into a dropping device which drops the wrappers into the rotary wrapper receiver; also to provide an improved and simplified wrapper dropping device.

Again it is an object to provide certain improvements in the straw hopper and to provide a machine that can be adapted for packaging straws of different lengths.

Other objects will in part be obvious and in part be pointed out hereinafter.

To the attainment of the aforesaid objects and ends invention also resides in the novel details of construction, combinations and arrangements of parts all of which will be first described in detail and then be specifically pointed out in the appended claims, reference being had to the accompanying drawings in which:

Figs. 1 and 1^A, when joined on the lines A—B, comprise a top plan view of that portion of a straw packaging machine which contains my invention.

Figs. 2 and 2^A, when joined on the lines a—b, comprise a vertical cross section on the line A—B in Fig. 1^A.

Fig. 3 is a detail vertical cross section on the line 3—3 of Fig. 1^A.

Fig. 4 is a detail horizontal section of the wrapper-severing (scissors) device taken substantially on the line 4—4 of Fig. 5.

Fig. 5 is a section on the line 5—5 of Fig. 4.

Fig. 6 is an elevation looking from right to left in Fig. 5.

Fig. 7 is a vertical cross section on the line 7—7 of Fig. 10 and looking from left to right in Fig. 1.

Fig. 8 is a cross section on the line 8—8 of Fig. 1.

Fig. 9 is an elevation of the transmission gearing and gear box with the cover removed.

Fig. 10 is a horizontal section on the line 10—10 of Fig. 9.

Figs. 11 to 14, inclusive, are somewhat diagrammatic views illustrating different positions of parts hereinafter specifically referred to.

Fig. 15 is an enlarged detail view, partly in

2

section, of one of the wrapper receiving members of the rotary carrier.

Fig. 16 is a plan view of one of the wrapper-engaging socket members carried by the slide-bars.

Fig. 17 is a longitudinal section of the same on the line 17—17 of Fig. 16.

Fig. 18 is a rear elevation of the same.

Fig. 19 is a front elevation of the same.

10 Fig. 20 is a view similar to Fig. 17, showing another form of wrapper-engaging member.

Fig. 21 is a front elevation of the same.

Fig. 22 is a detail perspective view of the eccentric shaft hereinafter referred to.

15 Fig. 23 is a detail side elevation of the mandrel and its associated elements.

Fig. 24 is an enlarged cross section on the line 24—24 of Fig. 23.

In the drawings in which like numerals of reference indicate like parts in all the figures, 1 represents the bed of the machine which is supported on standards (not shown) similarly to the bed 1 of the Toolan machine.

20 Mounted on the bed 1 is a casting having a base 2, spaced legs 3 and a head block 4. A bearing 6 projects from one leg 3 and, in connection with another bearing 35, supports the main shaft 5. The shaft 5 is held against longitudinal movement by collars 10, with set screws, and located one at each side of bearing 6 (Fig. 1^A). Fixed collars 11 and 12 are mounted on shaft 5 and determine the longitudinal setting of the shaft for short or long straw operation.

25 Spaced apart a predetermined distance (depending on the length of straws to be packaged) are two spiders 7 which are firmly secured to the shaft 5 and have arms 8 each carrying a pair of spaced-apart wrapper carrying members 9. The members 9 of one spider lining up with those of the other spider in directions paralleling the shaft 5.

30 As will best be seen by reference to Figs. 11 to 14, inclusive, the wrapper receiving members 9 are of generally semi-tubular form and include leading edges 9^x and following edges 9^y. The leading edges 9^x are closer to the center of the shaft 5 than are the following edges 9^y. It will also be observed that the wrapper catchers 76 are of semi-tubular form and the leading edges 76^x lie farther from the center of 51 than do the following edges 76^y. It will also be noted that the opening or mouth of the catcher 76 is directed laterally while the opening or mouth of the wrapper receiving member 9 is directed approximately radially so that the mouth of the

catcher 76, when the catcher is in the wrapper placed position Fig. 13, is approximately at right angles to the mouth of the receiving member 9. When in this position it will be observed that the leading edge 76^x of the catcher 76 is nearer the center of the shaft 5 than is the following edge 76^y and the following edge 76^y extends a greater distance from the center of the axle 5 than does the following edge 9^y. When the parts are in this position (Fig. 13) due to the foregoing structure, the following edge of the member 9 will drag the straw off the leading edge of the catcher 76. By virtue of the construction just described it has been found possible to dispense with the members numbered 86, 87, 88, 91 and 92 shown in the Toolan patent drawings and thus considerably simplify the construction of the machine as well as improve its efficiency of operation.

13 to 17, inclusive, are discs which carry the slide bars and straw pushers. The discs 14 to 17, inclusive, are secured to the shaft 5 while disc 13 is a ring-like disc and rides the periphery of the cam cylinder 23.

Pairs of guide bars 18 are secured to the discs 13 and 14, at 18^a (Fig. 10). Between these guide bars 18 the slide bars 19 operate.

The slide bars 19 are guided in slots in the discs 14, 15, 16 and 17 to which the slide bars are keyed, as in the Toolan patent aforesaid. Cross heads 20 operate between and are keyed to the guide bars 18 and have push bars 21 connected to the cross heads and lying in the grooves of the slide bars, being keyed to the slide bars as in the Toolan patent aforesaid by wings 22. The cam cylinder 23 has a groove 24 for operating the push bar and a groove 25 for operating the slide. The cam drum or cylinder 23 is held from turning with shaft 5, by a lock screw 32 carried by a bracket 33. The construction of the parts 13 to 25 may be substantially the same as corresponding parts of the Toolan machine and per se are not of my invention.

In the present machine, however, the funnel member (numbered 27 in the Toolan patent) is replaced by the wrapper-engaging member 26 shown in detail in Figs. 16 et al. This member includes a bell portion 27 on the front of an upright portion 28, the portions 27-28 having a passage through the same whose cross sectional shape is either elliptic (Figs. 17, 18, 19) or round (Figs. 20, 21) accordingly as two straws or one straw is to be placed in a wrapper.

The straw-entrance part 29 of the passage is tapered as shown and a shoulder 30 is provided against which the wrapper end abuts previously to receiving a straw (see dotted straw end S Fig. 17). Countersunk holes 31 are provided for fastening screws. I make no claim to the funnel member just described as that is not a part of my invention.

34 designates a housing for the gearing that connects a driving shaft (first motion) with the several operating shafts 5, 39 and 81, see Figs. 9 and 10 by reference to which it will be seen that the shaft 5 carries a large spur gear 36 and a smaller spur gear 37, the former meshing with a pinion 96 on an idler shaft 94 and the latter meshing with a pinion 38 on a delivery shaft 39. The housing has a bearing 98 for shaft 39, and other bearings 85 and 97 for other shafts which shall later again be referred to. A cover 99 is provided for the housing, which cover has a socket 100 to receive the end of shaft 5 when it is projected thereinto when the shaft is moved to

bring collar 11 against collar 10 on adapting the machine for packaging long straws. (As shown in the drawings the machine is adapted for packaging short straws.)

5 The shaft 39 extends along the machine and is journaled in bearings in brackets 45. It carries suitably spaced and located knurling rolls 40 and a pair of discs 41 having lifting and discharging arms 42 which cooperate with guide and stripping fingers 43 secured to a rod 44 located above the shaft 39. The rod 44 is fixedly secured in the bearing posts 45. The arms 42 deliver the packaged straws onto inclined rods 55 which are carried by a rod 56 held in brackets 57 secured by cap screws 58 to the bed. The rods 55 convey the packages to the receiver 59.

Transversely adjustably mounted on the supports 45 are brackets 60 each having bearing portions 61 in which is pinned a short shaft 62 carrying a sleeve bearing 63 of a bell crank lever 64, 66. Each lever leg 66 carries, on a stud 68, a freely rotatable knurling roller 67. The rollers 67 respectively cooperate with the rollers 40 to effectively seal the wrapper ends as in the patented Toolan machine. The adjusting arms 64 of the bell crank lever are provided to cooperate with springs 70 in sockets 65 and 69, and adjusting screws 71 are also provided.

Arms 48 having bearing sleeves 46 are rockably held in place on the rod 44 by collars 47. The arms 48 at their free ends have sleeves 49 to hold a rod 51 which rod is pinned to the sleeves 49 as at 50. The sleeve 46 also has an arm 52 which adjustably carries a cam-engaging roller 53. This roller is held in engagement with a cam 54 on the shaft 39 by a spring 72 engaging a pin 73 and anchored to bracket 45.

The rod 51 carries two split clamps 74 which carry the wrapper catchers and droppers. The clamps are secured to the rod by means of cap screws 75. Into each clamp is socketed and axially adjustably mounted the shank 77 of a wrapper catcher and dropper 76. A cap screw 78 serving to secure the shank in the respective clamp member. The sockets are so positioned on the rod 51 that the catcher and dropper 76 will pass between the furcations of the arms 8 of the rotary carrier spiders (see Fig. 1A).

79 are the wrapper restraining guides which prevent the wrappers from falling out of the wrapper-receiving members 9 as the carrier rotates. An abutment 80 is provided against which the following ends of the wrappers are held when the members 27 are brought into engagement with the forward ends of the wrappers prior to the straws being pushed into the wrappers.

The shaft 81 (which corresponds to the shaft 219 of the Toolan patent) operates the paper printing, feeding and wrapper forming mechanisms. As the printing mechanism is no part of the present invention it has not been illustrated in the accompanying drawings or described in this specification. The shaft 81 is journaled in suitable bearings 82 and 141 and carries a spur gear 83 which meshes with a gear 86 on a counter-shaft 84 journaled in bearing 85. The counter-shaft carries a sprocket 87, which is driven from the first motion shaft (not shown) by a chain 88. The shaft 84 also carries a spur gear 89 which meshes with a gear 91 on an idler shaft 90. A smaller gear 92 formed with gear 91 meshes with the larger 95 of a double pinion, the smaller one 96 meshing with gear 36. Collars 93 hold shafts 90 and 94 in place, the shafts 90 and 94 being fastened to their respective gears.

The wrapper severing mechanism which comprises an essential feature of my invention will best be understood by reference to Figures 1^A, and 3 to 6, inclusive. Mounted on a slide rod 123 by pins 125 and a cap screw or bolt 124 is a bracket 101, 122 having ears 102 in which the scissors carrying bolt 103 is held by a nut 107. The scissors backs 104 are pivoted on the bolt 103 and held together yieldably by the use of a tensioned washer 106. Each back carries a suitably tempered and sharpened blade 105. Each back 104 also has an arm 108. The arms 108 extend in opposite directions and are engaged by the cam ends 112 of a pair of fingers 111 carried by a rod or stem 114 which is mounted to slide in a bearing 115 of the bracket 101. The arm 108 has its end slotted as at 109 to receive an end of a spring 121. The said end is anchored in the slot by a pin 110. The fingers 111 are similarly slotted and also have spring-receiving sockets 113 in which the springs 121 lie. The other ends of the springs 121 are anchored to the bearing 115 by pins or posts 120. The outer end of the stem 114 is drilled and tapped, as at 116, to receive a headed screw 117 which is adjustable and held locked by a nut 119.

The head 118 of the screw 117 engages the head 149 of a bell crank lever 148 that is pivoted at 147 to a bracket 145 that is mounted on the support 4. The lever 148 has a roller 150 that is held in engagement with a cam 151 on shaft 81, by a spring 152. The cam effects the closing and affects the opening of the scissors, the closing being affected by the springs 121. It will be observed by reference to Fig. 1^A that the head 149 is elongated to allow for the travel of the severing devices with the wrapper for a predetermined distance.

The bar 123 is mounted in a slot 126 in the head 4, covered by a plate 127 (Fig. 3) and at its end remote from the bracket 101 it has an angled extension 142 having a hole through which passes a pin 143 that is secured to the head 4. A spring 144 continuously tends to move the bar 123 toward its normal rest position (right hand side Fig. 1^A).

The bar 123 carries a stud 128 on which is pivoted a slide block 129 which moves in the fork of a lever 130. The lever 130 is pivoted on a stud shaft 132 between a boss 131 and a collar 133 and held by a nut 134. The lever also carries a cam-engaging roller 138 that engages a cam 137 on a shaft 136 that is mounted in bearings 135 in the support 2, 3 hereinbefore mentioned. The shaft 136 carries a bevel gear 139 which meshes with a bevel gear 140 on the shaft 81.

The straw hopper and feeding mechanism also involves improvements of my invention and by reference to Figs. 1, 7 and 8 it will be seen that the hopper 163 is mounted rigidly on the supports 210 and has fixed side walls 167 and a laterally adjustable side wall 164 so that the same hopper can be used for long as well as short straws accordingly as the wall 164 is held against the adjacent end wall 167 or spaced therefrom (Fig. 1). The wall 164 is supported from the adjacent wall 167 by bolts 212 and spacing sleeves 211. The bottom of the hopper inclines downwardly and extends beyond the side walls 167 as at 135 to contact the discs 14, 15 and 16 (Fig. 8). Each side wall 164, 167 has a hole 166 through which passes the brush carrying shaft 165 on which suitably spaced brushes 184 are adjustably mounted.

The brush-carrying shaft 165 is journaled in

bearings of adjustable-angle levers 168—169 that are pivoted on studs 170 on the outer faces of the sides 167 (Figs. 1 and 7).

A shaft 172 is journaled in bearing bosses 171 on the sides 167 and passes through the hopper parallel to the shaft 165. The shaft 172 has seats 191 in which agitator fingers 190 are secured by screws and washers 192. An arm 173 is secured to shaft 172 and carries a roller 174 that is held by a spring 183 in engagement with a triangle cam 175 that is mounted on shaft 165. A belt pulley 176 is also mounted on shaft 165.

A standard 177 carries a pin 178 that has an eccentric shaft 179 on which two loose belt pulleys 180 are mounted side by side. An endless belt 182 passes around a pulley 181 on shaft 81, over pulleys 180 and around pulley 176 for driving shaft 165 and effecting operation of rock shaft 172.

By reference to Figs. 1 and 8 it will be seen that angle plates 186 are secured to one wall 167 and to the wall 164. These plates parallel the extended portion 185 of the hopper bottom and are spaced from the same slightly more than the diameter of a straw. The outer edge 187 of each plate 186 is curved down overhanging the edge 185 so as to lie sufficiently close to the discs 14, 15 and 16 to prevent passage of a straw between the peripheries of the discs and the plates 187. The rear ends of the plates 186 are bent upwardly as at 188 and parts cut away as at 189 to clear the agitator fingers 190.

193 illustrates the mandrel about which the continuous wrapper is formed and longitudinally sealed by the knurling wheels 194 and 195. The wheel 195 is carried on a shaft 196 journaled in bearings 198 supported on the head block 4 and driven at a predetermined speed by means of worm gears 197, 199 via a countershaft 200 that is mounted in a bearing in a support 201 mounted on the head block 4. The shaft 200 has a spur gear 204 that meshes with a larger gear 203 on a shaft 202. The shaft is suitably driven in harmony with the printing and paper feeding mechanism in any desired way.

Referring now to Figs. 1^A and 3 it will be seen that the mandrel 193 is provided adjacent, but in advance of, the knurling or crimping wheel 194, and carries a suitable paper folder 153 through which the paper strip is threaded and formed into a tubular structure. The mandrel 193 is held at 157, to a block 154 having a passage through which the paper strip is fed beneath the mandrel to the folder 153 and over the guide 162 which is pivoted in a forked block 160 that is held by a set screw 161 in the socket 205 of a bracket 206 attached to support head 4. The bracket 206 also has a socket 207 in which the shank 156 of the block 154 is held by a set screw 157. A bar 158 is secured to block 154 and carries an adjusting screw 159 by which mandrel 193 may be levelled or tilted as desired, mandrel 193 being pivoted to pin 157 on a horizontal axis as at 208.

65 Resilient wires 209 are mounted on the wrapper restraining guides 79 to hold the wrappers and straws therein in place on the carrier while the sockets 27 are being withdrawn. As these wires are not of my invention no claim thereto is made herein.

Operation

The continuous strip of paper from the printing mechanism (not shown) is fed through the opening in block 154 and around mandrel 193

through the folder 153 which overlaps the longitudinal edges and passes the same between the knurling or crimping wheels 194 and 195 where the overlapped edges are crimped together forming a continuous wrapper.

Referring now to Figs. 11 to 14, 1 and 1A, it will be seen that when the rotary carrier is in the position shown in Fig. 11, the wrapper receiving member 9 of leg A will be empty, the straw slide 19 corresponding therewith will be all the way back, the straw pusher 21 will be about two-thirds the way back, the cutting mechanism will be all the way back with its scissors all the way open.

As the leg A passes from the position shown in Fig. 11 and is about to reach the position Fig. 12, the scissors begin to close and start their advance, the cutting off of a length of wrapper occurs and the lower blade 105 impells the cut length of wrapper into the catcher, the scissors reaching their fully advanced position (Fig. 1A) at the time leg A reaches the position of Fig. 12. The cutting action of the scissors is almost instantaneous so the blades 105 are fully separated by the time leg A reaches position Fig. 12.

As leg A leaves the position Fig. 11 catcher 76 starts to swing down and by the time it reaches position Fig. 12 the cut wrapper will have been deposited in the catcher.

Passing from the position shown in Fig. 11 to that shown in Fig. 12 the slide 19 corresponding to leg A starts to advance, while straw pusher 21 associated with that slide continues to move backward (right to left in Fig. 1) so that by the time leg A reaches the position of leg B in Fig. 11, the pusher will be all the way back (by this time also the slide 19 will have advanced about one-half way). As soon as the pusher 21 is all the way back straws from the hopper 163 are placed in the slide 19. In passing from the position Fig. 13 to the position of Fig. 14 the wrapper W is carried out of the catcher which catcher thereafter starts to swing up again to the position of Figs. 11 and 14.

By the time leg A reaches the position of leg C in Fig. 11 the slide 19 will have fully advanced and bell portion 27 will have been placed over the advance end of the wrapper and the other wrapper end pushed loosely against the abutment 80 and thus the wrapper is centered in the carrier. Also at this time the scissors will be all the way back (moving from left to right in Fig. 1A).

As leg A reaches the position of leg C in Fig. 11 the straw pusher 21 will be pushing the straws into the wrapper via member 27. The slide 19 remains in the fully advanced position until the leg A reaches the position of leg E in Fig. 11 whereupon it starts to recede. The straw pusher continues forward until leg A reaches the position of leg E and then starts back with the slide 19. Both the slide 19 and pusher 21 reach their farthest back positions about the time leg A reaches the position of leg F in Fig. 11. As leg A approaches the position of leg E in Fig. 11 and before slide 19 starts back the filled wrapper in carrier 9 will be held in the carrier by the spring 209 long enough for the member 27 to be withdrawn from the end of the filled wrapper.

On leg A passing from the position of leg E in Fig. 14 the ends of the wrapper are passed between the end sealing, crimping or knurling rollers 67 and 40 and securely crimped shut, after which the filled wrappers are removed (as in the Toolan machine) by the arm 42 and de-

5 6 7 8 9 10 11 12 13 14 15 16 17 18 19 20 21 22 23 24 25 26 27 28 29 30 31 32 33 34 35 36 37 38 39 40 41 42 43 44 45 46 47 48 49 50 51 52 53 54 55 56 57 58 59 60 61 62 63 64 65 66 67 68 69 70 71 72
